(57) **CLAIM**

I claim the ornamental design for a wireless audio video jack, as shown and described.

DESCRIPTION

FIG. 1 is a rear elevation of a wireless audio video jack showing my new design;

FIG. 2 is a front elevation thereof;

FIG. 3 is a left side elevation thereof;

FIG. 4 is a right side elevation thereof;

FIG. 5 is a top plan view thereof;

FIG. 6 is a bottom plan view thereof; and,

FIG. 7 is a perspective view thereof.

1 Claim, 7 Drawing Sheets

FIG. 2

FIG. 3

FIG. 4

FIG. 6
